STRAP TIGHTENER

Arthur F. Bernard, Providence, R. I.

Application October 25, 1932. Serial No. 639,509

18 Claims. (Cl. 24—71)

My invention relates to improvements in strap tighteners, adapted for use in encircling straps, preferably a limb encircling strap, such as a bracelet, which will readily open up to permit 5 the easy removal of the bracelet from the wrist.

A feature of my invention relates to improvements in strap tighteners of this description, providing a structure employing a slidable adjustable member in the strap tightener so that 10 the strap tightener may be laid in closed position on the wrist or other member and the slidable member moved inwardly relative to the strap tightener after the strap tightener itself has been closed to adjust the strap to the desired length for 15 free play of the wrist in use.

A further feature of my invention is to provide a structure wherein the length adjusting means also provides the supplemental function of locking the top and bottom connector sections of the 20 strap tightener together.

Further features of my invention relate to the improved specific structural details of the strap tightener hereinafter described.

A further object of my invention is to provide 25 a strap tightener which in use, although it may be made up of a top, one or more intermediate and a bottom connector section, in use presents the appearance of but a single thickness when viewed from the side, thereby providing a strap tightener of this construction of the thinnest 30 type of any known on the market.

These and such other objects of my invention as may hereinafter appear will be best understood from a description of an embodiment thereof, such as is shown in the accompanying drawing.

In the drawing, Fig. 1 is a plan view of my improved strap tightener in use with my improved slidable member in a position spaced away 40 from the top and bottom connector sections as would normally be adjusted in use on a bracelet.

Fig. 2 is a sectional view taken along the line 2—2 of Fig. 1.

Fig. 3 is a sectional view of the embodiment of 45 my invention shown in Fig. 2 with the top connector section raised away from the bottom connector section for the purpose of opening the strap tightener for removal of the bracelet.

Fig. 4 is a longitudinal sectional view partially shown in elevation taken along the line 50 4—4 of Fig. 2.

Fig. 5 is a cross sectional view taken along the line 5—5 of Fig. 4.

Fig. 6 is a sectional view of the resilient cam means I preferably employ in locked position in

a hole in a vertically projecting wall of the bottom connector section.

Fig. 7 is a side elevation generally similar to Fig. 6 showing the slidable member in the act of being moved inwards with the resilient cam 60 means depressed into the slit to permit contraction of the cam means for this purpose.

Fig. 8 is a perspective view of the end of the rod member showing the longitudinal slit and laterally projecting resilient cam means. 65

Fig. 9 is a cross section taken along the line 9—9 of Fig. 8.

Fig. 10 is a diagrammatic sectional view somewhat similar to Fig. 4 of a different embodiment of my invention showing a construction of the 70 resilient cam means which can be used without the slits.

In the drawing, wherein like characters of reference indicate like parts throughout, 20 generally indicates a strap tightener constructed in 75 accordance with my invention. My improved strap tightener preferably includes a top connector section 22 and a bottom connector section 24. I employ means to pivotally attach said top connector section to said bottom connector section. In my improved embodiment said means preferably comprises one or more intermediate connector sections having the ends thereof pivotally attached to the inner ends of said top and bottom connector sections. In my pre- 80 ferred embodiment I preferably employ the intermediate connector section 26 pivotally attached as at 28 and 30 respectively to the inner ends of the top and bottom connector sections. 85

One of said connector sections, preferably the 90 bottom connector section as in the embodiment shown is provided with means 32 to attach the strap end 34 thereto and a wall 36, in my preferred embodiment two, projecting substantially vertically therefrom for a substantial distance 95 having the spaced holes 38 therein and the other of said connector sections in my preferred embodiment, preferably the top connector sections 22 is provided with means 40 to attach the other strap end 41 thereto, said means 40 being prefer- 100 ably slidable on said top connector section 22 and having cam means 42 resilient in its action projecting laterally therefrom. Each cam means 42 comprises cam surfaces 46 which may be considered as positioned in vertical planes, and paired cam surfaces 47, which may be considered as positioned in planes converging toward the horizontal, as described in more detail below.

In the preferred embodiment shown in order that my improved strap tightener may be as thin 110

as possible and present a single thickness when viewed from the side, I preferably provide the top connector section with the side walls 48 projecting first downwardly as at 50, then inwardly 5 as at 52 and having at least a portion 54, preferably near the outer end thereof projecting upwardly, said bent side walls thus forming channels 56 on each side of the top connector section. In my preferred embodiment I also preferably 10 construct the bottom connector section 24 of lesser width than said top connector section and provide it with the side walls 36 projecting upwardly therefrom, each having the sets of aligned spaced holes 38 therein. With this construction 15 therefore it is obvious that the bottom connector section may be pivoted to a position intermediate the channels 56 of said top connector section as shown in Fig. 5 to form when viewed from the outside substantially a single thickness and a 20 strap tightener of lesser thickness than any hitherto known on the market. In my preferred embodiment, the means 40 slidable relative to said top connector section 22 adapted to have the other strap end 42 attached to the end thereof, preferably comprises a U-shaped bail member 25 having the other strap end pivotally attached to the U-base 58 thereof and the U-legs 60 thereof slidably constrained within the channels 56. I then preferably construct two resiliently acting 30 cam means 42 projecting inwardly from the inner end of each respective U-leg 60. In order that the cam means may act resiliently, I preferably provide the inner end of each leg 60 with the longitudinal slit 62. Each cam means 42 is provided 35 with three cam surfaces, as shown more particularly in Fig. 8. The first cam surface, indicated at 46, may be considered as located in a vertical plane, and slants toward the inside of member 60, and it is this cam surface 40 that bears or cams against the edges of the holes 38 and causes the inward bending of the U-leg 60, as shown in Fig. 7. The other two cam surfaces, indicated at 47, may be considered as located in converging diagonal planes, see Figs. 45 8 and 9. It is these cam surfaces 47 that function when the parts are moved from the open position of Fig. 3 to the closed position of Fig. 2, and vice versa. In such movement, see Fig. 5, the metal defining the upper edge of the holes 50 38, Fig. 3, bears against the cam surfaces 47 on both sides of U-leg 60 and pushes them inwardly, to a position like that in Fig. 7; the legs then spring out again and lock the parts together, as in Fig. 2. When this locking has been accomplished, the U-leg 60 can still be moved inwardly 55 for adjustment, through the action of cam 46 and cooperating parts.

The cams 42, composed of the sets of cam surfaces 46 and 47, and their cooperating parts, therefore form a combined locking and adjusting means.

In order to attach my improved strap tightener with strap attached thereto, such as in a bracelet, it is merely necessary to pivot the strap tightener to an open position suggested in Fig. 3 to bring the top connector section 22, intermediate connection 26 and bottom connector section 24 into horizontal alignment so that the bracelet 65 may be moved over the hand to the desired position on the wrist. When the bracelet lies on the wrist, it is obvious that the top connector section may be pivoted over the bottom connector section to a closed position.

As my improved strap tightener is made for any size wrist in order to adjust the strap accu-

rately to the wrist the U-shaped bail member 40 is first pulled way outwards so that the cam means 42 thereof will project inwardly of the innermost aligned set of holes 38 therein. It is obvious that as the top connector section 22 is brought into position over the bottom connector section 24 that the side walls 36 of said bottom connector section will slide intermediate the upwardly projecting portions 50 of the side walls 48 of the top connector section and thus take a position interior of said channels 56. When the bottom connector section has assumed this position it is obvious that the resilient cam means 42 is resilient in my preferred embodiment due to longitudinal slits 62 will expand outwards to permit the bottom connector section to achieve this position and that when it has achieved this position the resilient cam means will resiliently spring inwardly within the innermost aligned holes 38. In order to adjust the links of the bracelet or strap to the wrist it is apparent that the bail member 40 may be merely pushed outwards, the resilient cam means 42 resiliently expanding as suggested in Fig. 7 to permit the cam means 42 to slide over the desired number of 100 sets of aligned holes until the desired length of the bracelet has been achieved, when the cam means 42 will immediately spring inwards into the desired set of aligned holes, thereby adjusting the strap tightener and attached strap to the 105 desired length for convenient use on the wrist and providing a construction which once adjusted will not pull out to a longer length. To remove the strap or strap tightener from the wrist or other object it is obvious that it is 110 merely necessary to raise up the top connector section from the bottom connector section against the pressure of the cams 42 and as the cam means has tapered upper and lower sides, it is obvious that it provides a lateral cam which may readily 115 give for this purpose until the resilient cam means is entirely moved out of the set of aligned holes 38, thereby permitting the top connector section and intermediate connector section to be pivoted into a substantially horizontal alignment 120 for removal of the strap and strap tightener from the wrist or other object. It is apparent therefore that I have provided a novel type of strap tightener in which the same means functions as a catch for holding it together and as 125 an adjustment to adjust the strap to the desired length, constructed of a minimum number of simple parts and relatively easy to construct.

I employ the words "inner" and "outer" in reference to the intermediate connector section 130 when the top and bottom connector sections are pivoted in substantially horizontal alignment to the open position suggested in Fig. 3 and inwardly and outwardly relative to the longitudinal center line thereof.

It is understood that my invention is not limited to the specific embodiment shown and that various deviations may be made therefrom without departing from the spirit and scope of the appended claims.

What I claim is:

1. In a strap tightener, a top connector section, a bottom connector section, means to pivotally attach said top connector section to said bottom connector section, one of said sections 145 having means to attach a strap end thereto and a wall projecting substantially vertically therefrom for a substantial distance having spaced holes therein and the other of said sections having means to attach the opposite strap end there- 150

- to, said latter attaching means slidably mounted in said other section and having resilient cam means projecting laterally therefrom, said cam means having a flat outer wall and an inwardly 5 tapered side wall, whereby when said bottom connector section is brought into position underneath said top connector section said resilient cam means may spring into one of said holes to lock said sections together and permitting inward adjustment of said slidable means to shorten said strap and preventing outward movement of said slidable means relative to said locked connector sections. 10
2. In a strap tightener, a top connector section, a bottom connector section, means to pivotally attach said top connector section to said bottom connector section, said bottom connector section having means to attach a strap end thereto and a wall projecting substantially vertically therefrom for a substantial distance having spaced holes therein and said top connector section having means to attach the opposite strap end thereto, said latter attaching means slidably mounted in said top connector section and having resilient cam means projecting laterally therefrom, said cam means having a flat outer wall and an inwardly tapered side wall, whereby when said bottom connector section is brought into position underneath said top connector section, said resilient cam means may spring into one of said holes to lock said sections together, and permitting inward adjustment of said slidable means to shorten said strap and preventing outward movement of said slidable means relative to said 15 locked connector sections. 20
3. In a strap tightener, a top connector section, a bottom connector section, an intermediate connector section pivotally attached to the inner ends of said connector sections, one of said sections having means to attach a strap end thereto and a wall projecting vertically therefrom for a substantial distance having spaced holes therein and the other of said sections having means to attach the opposite strap end thereto, said latter attaching means slidably mounted in said other section and having a resilient cam means projecting laterally therefrom, said cam means having a flat outer wall and an inwardly tapered side wall, whereby when said bottom connector section is brought into position underneath said top connector section said resilient cam means may spring into one of said holes to lock said sections together, and permitting inward adjustment of said slidable means to shorten said strap and preventing outward movement of said slidable means relatively to said locked connector sections. 25
4. In a strap tightener, a top connector section, a bottom connector section, an intermediate connector section pivotally attached to the inner ends of said connector sections, said bottom connector section having means to attach a strap end thereto and a wall projecting substantially vertically therefrom for a substantial distance having spaced holes therein and said top connector section having means to attach the opposite strap end thereto, said latter attaching means slidably mounted in said top connector section and having resilient cam means projecting laterally therefrom, said cam means having a flat outer wall and an inwardly tapered side wall, whereby when said bottom connector section is brought into position underneath said top connector section, said resilient cam means may spring into one of said holes to lock said sections together and permitting inward adjustment of said slidable means to shorten said strap and preventing outward movement of said slidable means relative to said locked connector sections. 30
5. In a strap tightener, a top connector section, a bottom connector section, means to pivotally attach said top connector section to said bottom connector section, one of said sections having means to attach a strap end thereto and a wall projecting substantially vertically therefrom for a substantial distance thereof having spaced holes therein and the other of said sections having rod means to attach the opposite strap end thereto, said rod means slidably mounted in said other section and having resilient cam means projecting laterally from the inner end thereof, said cam means having a flat outer wall and a horizontal slit at the inner end thereof opposite said cam means, whereby when said bottom connector section is brought into position underneath said top connector section, said resilient cam means may spring into one of said holes to lock said sections together, and permitting inward adjustment of said slidable means to shorten said strap and preventing outward movement of said slidable means relative to said locked connector sections. 35
6. In a strap tightener, a top connector section having side walls projecting first downwardly, then inwardly and having a portion thereof near the inner end thereof projecting upwardly forming a channel in each side thereof and a bottom connector section of lesser width than said top connector section having side walls projecting upwardly therefrom having sets of aligned spaced holes therein, means to attach a strap end to said bottom connector section, means to pivotally attach said bottom connector section to said top connector section so that said bottom connector section may pivot to a position intermediate the side walls thereof with said top and bottom sections forming a single thickness, said top connector section having a U-shaped bail member having the outer strap end attached to the U-base thereof and the U-legs thereof slidably constrained within said channels, each leg having a longitudinal slit at the inner end thereof and resilient cam means projecting laterally inwardly thereof having a flat outer and an inwardly tapered side wall, whereby when said bottom connector section is brought into position underneath said top connector section, each of said resilient cam means may spring into one of said sets of aligned holes to lock said sections together and permitting inward adjustment of said slidable means to shorten said strap and preventing outward movement of said slidable means relative to said locked connector sections. 40
7. In a strap tightener, a top connector section having side walls projecting first downwardly then inwardly and having a portion thereof near the inner end thereof projecting upwardly forming a channel in each side thereof and a bottom connector section of lesser width than said top connector section having side walls projecting upwardly therefrom having sets of aligned spaced holes therein, means to attach a strap end to said bottom connector section, an intermediate connector section pivotally attached to the inner end of said connector sections so that said bottom connector section may pivot to a position intermediate the side walls of said top connector section with said top, intermediate, and bottom sections forming a single thickness, said top connector section having a U-shaped bail member having the other strap end attached to the U-base 45
- 75

- thereof and the U-legs thereof slidably constrained within said channels, each leg having a longitudinal slit at the inner end thereof and resilient cam means projecting laterally inwardly 50
- 5 thereof having a flat outer wall and an inwardly tapered side wall, whereby when said bottom connector section is brought into position underneath said top connector section, each of said resilient cam means may spring into one of said sets of aligned holes to lock said sections together and permitting inward adjustment of said slid- 80
- 10 able means to shorten said strap and preventing outward movement of said slid- able means relative to said locked connector sections. 85
- 15 8. In a strap tightener, a top connector section having side walls projecting first downwardly, then inwardly and having a portion thereof near the inner end thereof projecting upwardly forming a channel in each side thereof and a bottom 90
- 20 connector section of lesser width than said top connector section having side walls projecting upwardly therefrom having sets of aligned spaced holes therein, means to attach a strap end to said bottom connector section, an intermediate 95
- 25 connector section pivotally attached to the inner ends of said connector sections so that said bottom connector section may pivot to a position intermediate the side walls of said top connector section, said top connector section having a U-shaped bail member having the other strap end attached to the U-base thereof and the U-legs thereof slidably constrained within said channels, each leg having a longitudinal slit at the inner 100
- 30 end thereof and resilient cam means projecting laterally inwardly thereof having a flat outer wall and an inwardly tapered side wall, whereby when said bottom connector section is brought into position underneath said top connector section, said top connector section having a U-shaped bail member having the other strap end attached to the U-base thereof and the U-legs thereof slidably constrained within said channels, each leg having a longitudinal slit at the inner 105
- 35 end thereof and resilient cam means projecting laterally inwardly thereof having a flat outer wall and an inwardly tapered side wall, whereby when said bottom connector section is brought into position underneath said top connector section, each of said resilient cam means may spring into one of said sets of aligned holes to lock said sections together and permitting inward adjustment of said slid- able means to shorten said strap and preventing outward movement of said slid- able means relative to said locked connector sections. 110
- 40 9. In a strap tightener, a top connector section having side walls projecting first downwardly, then inwardly and having a portion thereof near the inner end thereof projecting upwardly forming a channel in each side thereof and a bottom 115
- 45 connector section of lesser width than said top connector section having side walls projecting upwardly therefrom having sets of aligned spaced holes therein, means to attach a strap end to said bottom connector section, an intermediate connector section pivotally attached to the inner ends of said connector sections so that said bottom connector section may pivot to a position intermediate the side walls of said top connector section, said top connector section having a U-shaped bail member having the other strap end attached to the U-base thereof and the U-legs thereof slidably constrained within said channels, each leg having a longitudinal slit at the inner 120
- 50 end thereof and resilient cam means projecting laterally inwardly thereof having a flat outer wall and an inwardly tapered side wall, whereby when said bottom connector section is brought into position underneath said top connector section, each of said resilient cam means may spring into one of said sets of aligned holes to lock said sections together and permitting inward adjustment of said slid- able means to shorten said strap and preventing outward movement of said slid- able means relative to said locked connector sections. 125
- 55 10. In a strap tightener, a top connector section having side walls projecting first downwardly, then inwardly and having a portion thereof near the inner end thereof projecting upwardly forming a channel in each side thereof and a bottom 130
- 60 connector section of lesser width than said top connector section having side walls projecting upwardly therefrom having sets of aligned spaced holes therein, means to attach a strap end to said bottom connector section, an intermediate connector section pivotally attached to the inner ends of said connector sections so that said bottom connector section may pivot to a position intermediate the side walls of said top connector section, said top connector section having a U-shaped bail member having the other strap end attached to the U-base thereof and the U-legs thereof slidably constrained within said channels, each leg having a longitudinal slit at the inner 135
- 65 end thereof and resilient cam means projecting laterally inwardly thereof having a flat outer wall and an inwardly tapered side wall, whereby when said bottom connector section is brought into position underneath said top connector section, each of said resilient cam means may spring into one of said sets of aligned holes to lock said sections together and permitting inward adjustment of said slid- able means to shorten said strap and preventing outward movement of said slid- able means relative to said locked connector sections. 140
- 70 11. In a strap tightener, a top connector section having side walls projecting first downwardly, then inwardly and having a portion thereof near the inner end thereof projecting upwardly forming a channel in each side thereof and a bottom 145
- 75 connector section of lesser width than said top connector section having side walls projecting upwardly therefrom having sets of aligned spaced holes therein, means to attach a strap end to said bottom connector section, an intermediate connector section pivotally attached to the inner ends of said connector sections, one of said sections having means to attach a strap end thereto and a portion having spaced holes therein and the other of said sections having means to attach another strap end thereto, said latter attaching means being slidably mounted in said other section and having resilient cam means projecting laterally therefrom, said cam means having a flat outer wall, whereby when said bottom connector section is brought into position underneath said top connector section, said resilient cam means may spring into one of said holes to lock said sections together. 150

to shorten said strap and preventing outward movement of said slidable means relative to said locked connector sections.

14. In a strap tightener, a top connector section, a bottom connector section, an intermediate connector section pivotally attached to the inner ends of said connector sections, said bottom connector section having means to attach a strap end thereto and a portion having spaced holes therein and said top connector section having means to attach the opposite strap end thereto, said latter attaching means slidably mounted in said top connector section and having resilient cam means projecting therefrom, said cam means having a flat outer wall and an inwardly tapered side wall, whereby when said bottom connector section is brought into position underneath said top connector section, said resilient cam means may spring into one of said holes to lock said sections together and permitting inward adjustment of said slidable means to shorten said strap and preventing outward movement of said slidable means relative to said locked connector sections.

15. In a strap tightener, a top connector section, a bottom connector section, means to pivotally attach said top connector section to said bottom connector section, one of said sections having means to attach a strap end thereto and a portion having spaced holes therein and the other of said sections having rod means to attach the opposite strap end thereto, said rod means slidably mounted in said other section and having resilient cam means projecting from the inner end thereof, said cam means having a flat outer wall and an inwardly tapered side wall and a horizontal slit at the inner end thereof opposite said cam means, whereby when said bottom connector section is brought into position underneath said top connector section, said resilient cam means may spring into one of said holes to lock said sections together; and permitting inward adjustment of said slidable means to shorten said strap and preventing outward movement of said slidable means relative to said locked connector sections.

45

16. In a strap tightener, a top connector section, a bottom connector section, means for pivotally attaching said connector sections together, each of the connector sections having means for attaching a strap end thereto, one of the connector sections including a variably positionable member slidable therein, combined locking and adjusting means carried by the said variably positionable member and by the other connector section, said combined locking and adjusting means serving to secure the two connector sections together, and to permit variable positioning of the slidable member.

17. In a strap tightener, a top connector section, a bottom connector section, an intermediate connector section pivotally attached at its opposite ends to both connector sections, each of the connector sections having means for attaching a strap end thereto, one of the connector sections including a variably positionable member slidable therein, combined locking and adjusting means carried by the said variably positionable member and by the other connector section, said combined locking and adjusting means serving to secure the two connector sections together, and to permit variable positioning of the slidable member.

18. In a strap tightener, a top connector section, a bottom connector section, means for pivotally attaching said connector sections together, each of the connector sections having means for attaching a strap end thereto, one of the connector sections including a variably positionable member slidable therein, combined locking and adjusting means carried by the said variably positionable member and by the other connector section, said combined locking and adjusting means including two sets of cams, one set for use in locking the two connector sections together, and the other set for use in permitting inward adjustment of the slidable member, but preventing outward movement thereof.
